CLAIM

The ornamental design of a hangable aquarium filter as shown and described.

DESCRIPTION

FIG. 1 is a perspective view of a hangable aquarium filter embodying the invention.

FIG. 2 is a front view of the hangable aquarium filter of FIG. 1.

FIG. 3 is a rear view of the hangable aquarium filter of FIG. 1.

FIG. 4 is a first side view of the hangable aquarium filter of FIG. 1.

FIG. 5 is a second side view of the hangable aquarium filter of FIG. 1.

FIG. 6 is a top view of the hangable aquarium filter of FIG. 1; and,

FIG. 7 is a bottom view of the hangable aquarium filter of FIG. 1.

The portions of the hangable aquarium filter shown in broken lines are for illustrative purposes only and form no part of the claimed design.
